US00D892751S

(12) **United States Design Patent** (10) **Patent No.:** **US D892,751 S**
Altonen et al. (45) **Date of Patent:** **** Aug. 11, 2020**

(54) **CONTROL DEVICE**

(71) Applicant: **Lutron Technology Company LLC**,
Coopersburg, PA (US)

(72) Inventors: **Gregory Altonen**, Easton, PA (US);
Chris Dimberg, Easton, PA (US);
Jason C. Killo, Emmaus, PA (US);
Brad Michael Kreschollek, Bethlehem,
PA (US); **Matthew Philip McDonald**,
Phoenixville, PA (US)

(73) Assignee: **Lutron Technology Company LLC**,
Coopersburg, PA (US)

(**) Term: **15 Years**

(21) Appl. No.: **29/697,939**

(22) Filed: **Jul. 12, 2019**

(51) **LOC (12) Cl.** **13-03**

(52) **U.S. Cl.**

USPC **D13/171**; D13/168

CLAIM

The ornamental design for a control device, as shown and described.

DESCRIPTION

FIG. 1 is a front perspective view of a control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines illustrate structure or features which form no part of the claimed design.

1 Claim, 4 Drawing Sheets
